UNITED STATES PATENT OFFICE

ERNEST BURNAND, OF PARIS, FRANCE

PLATE SPRING

Application filed November 25, 1929, Serial No. 409,707, and in Germany November 29, 1928.

The present invention relates to plate springs, and chiefly to the springs employed for the suspension of vehicles.

The invention consists in interposing an auxiliary plate between the ordinary plates of the spring, and in the use of means such that the variations of deflection of said spring will cause a considerable slipping of the auxiliary plate with reference to the main set 10 of plates, and since this slipping is impeded by the friction of the auxiliary plate upon the adjacent plates, the movements of the spring will be themselves impeded.

To obtain this result, I preferably dispose, 15 within the set of plates, an auxiliary plate which is cut off at a point near the center, and is connected at the outer end to the corresponding end of the main plate, and thus the auxiliary plate is actuated by the main 20 plate with a relative movement which absorbs a considerable work of friction, said auxiliary plate being pressed against other spring plates upon its whole length and upon both faces.

25 The effect of friction and hence the impeding action will be the greater according as a greater number of intermediary plates separate the actuated auxiliary plate from the plate to whose end it is attached.

30 The connection between the auxiliary plate and the main plate may be effected with the interposition of a play or elastic packing, or by a rigid mounting.

35 The accompanying drawings show by way of example a spring according to the present invention, and herein the auxiliary plate is secured to the main plate without play, and by winding it about the axle.

40 Fig. 1 is a cross sectional longitudinal view of the spring;

Fig. 2 is a cross sectional view taken at right angles to Fig. 1 looking towards the center of the spring from a point outside of 45 the cross pieces 14; and,

Fig. 3 is a partial elevational view of a detail.

In this example, the auxiliary plate 1 extends from the outer end of the spring as far 50 as a sectioned place 2 adjacent the middle

axis of the spring. Between this auxiliary spring plate and the main plate 3 is interposed one of the spring plates 4 of the general set of plates forming the spring, and the remainder 5 are disposed below the auxiliary plate.

The said auxiliary plate is secured to the main plate by winding it at 6 about the spring eye 7 of the spring, as is the main plate itself.

Suitable pressing plates 8 are disposed above and below the spring and are held by a strap or clip which maintains the plates in close contact at a certain pressure.

The said plates are preferably provided 65 with perforations 10 which are in communication and are supplied by an oiler 11.

According to a preferred disposition for fixing the plates and the clips, such clips consist of two end plates provided with apertures into which are inserted the ends of cross-pieces 14. In each cross-piece are two notches 15 into which are fitted the walls corresponding to the apertures of the plates 12; 70 the elastic effect of the spring plates 8 is sufficient to maintain the cross-pieces in the plates 12. This arrangement affords a ready 75 construction.

Having now particularly described and ascertained the nature of my invention and 80 in what manner the same is to be performed, I declare that what I claim is:

1. A plate spring comprising an auxiliary plate connected to the end of the main plate, 85 it being interposed in the set of spring plates and slideable with reference to said plates.

2. A plate spring as claimed in claim 1, in which at least one of the plates of the set is inserted between the main plate and the 90 said auxiliary plate.

3. A plate spring as claimed in claim 1, in which the several plates are pressed together, in order to increase the friction, by small plates situated on each side of the set of 95 spring plates which are held by flanges.

4. A spring plate as claimed in claim 1, in which the several plates are pressed together, in order to increase the friction, by small plates situated on each side of the 100

set of spring plates, which are held by flanges, consisting of two cheeks connected together by cross-pieces whose ends comprise a notch fitting into a corresponding part of the said cheeks.

5 In testimony whereof I have signed this specification.

ERNEST BURNAND.
